UNITED STATES PATENT OFFICE.

GEORGE G. PRENDERGAST, OF ST. LOUIS, MISSOURI.

APPARATUS FOR MOVING DERRICKS AND THE LIKE.

Application filed May 13, 1921. Serial No. 469,387.

To all whom it may concern:

Be it known that I, GEORGE G. PRENDERGAST, a citizen of the United States, and resident of the city of St. Louis and State of Missouri, have invented certain new and useful Improvements in Apparatus for Moving Derricks and the like, of which the following is a specification containing a full, clear, and exact description, reference being had to the accompanying drawings, forming a part hereof.

My invention relates to improvements in apparatus for moving derricks and the like, and has for its primary object a pair of skids constructed of a frame work of timbers and closed at their bottom so that the same will not sink into soft soil.

A further object is to construct a pair of skids on which a traveling derrick is mounted, the skids being so arranged as to be moved as the work progresses.

In the drawings,

Fig. 1 is a side elevation of my device, showing the manner of mounting the derrick thereon.

Fig. 2 a top plan view of the same.

Fig. 3 a top plan view of one of the skids before the supporting track is laid thereon.

Fig. 4 is a bottom plan view of the same.

Fig. 5 a side elevation of one of the jacks made use of to relieve the pressure on the skids while the same is being moved, parts thereof being broken away and in section.

In the construction of my device I employ a pair of skids 6 and 7. These skids are constructed of heavy timbers and comprise a central timber 8 and side timbers 9. These timbers are bolted together as indicated by the bolts 10, so that the skid can be built of any desired practical length. The timbers 8 and 9 are spaced apart by means of blocks 11. The whole being secured together by means of bolts 12 which pass through the side timbers 9 and central timber 8 and the blocks 11. Each end of the timbers as well as the blocks adjacent thereto is inclined as at 13. When the frame has thus been assembled, the entire bottom is closed by means of boards 14, thus making each skid resemble a flat-boat. This construction prevents the skids from sinking into soft soil and the width of the skids can be regulated according to the class of ground on which they are to be used. Placed over the timbers 8 and 9 are cross-bars or ties 15 and on these ties are secured rails 16. These

rails act as a runway for wheels 17 which are mounted on the underside of a platform 18. This platform may be constructed of any desired material, but is preferably built up of steel. Secured to one end of the platform 18 is an A frame 19 which is braced by means of the stiff legs 20. Pivoted mounted between the legs of the A frame is a boom 21. This boom is adapted to be raised and lowered by means of cables 22. The boom is also provided with hoisting cables 23 which hoist the load. In the present instance as shown in the drawing, this load is the clam shell bucket 24, although an ordinary hook may be substituted where it is desired to handle stone, timber or the like. Mounted on the platform 18 is a hoisting engine 25. This hoisting engine is provided with drums 26 and 27 and with nigger heads 28 and 29. In the present instance, I have shown a two drum hoisting engine, although it is obvious that various types of engines, ranging from a single drum to any desired number of drums, may be employed. This hoisting engine not only operates the derrick, but is also used to shift the skids and to move the derrick on the skids. Secured on the platform and projecting to the rear thereof, is a plurality of timbers 30, which timbers act as a base for the engine and are preferably floored over so as to provide a platform for fuel and other necessities to be carried with the derrick and the engine. The timbers 30 are joined together near their rear ends with a timber 31 and to this timber are swingingly attached snatch blocks 40 and 41. Around these snatch blocks pass cables 34 and 35. These cables have their ends 36 and 37 secured to the timber 31. The cables are then passed forward to the front end of the skid, where they pass around sheave wheels 38 and 39. These sheave wheels are secured in advance of the front end of the skid and directly in front of the rails 16 so that the skid will be pulled straight backward. After passing around the wheels 38 and 39, the cables 34 and 35 pass around the snatch blocks 40 and 41 as previously stated. The cable 34 then passes around snatch block 40 and both cables may be then wrapped around the nigger heads. Secured near each end of the platform 18 are sockets 42 through which are inserted bars 43. These bars are provided near their outer ends with a screw threaded casting 44, through which a jack screw 45

passes. This jack screw is provided on its lower end with a plate 46 which is preferably pivotally secured to the screw 45. The upper end of the screw is provided with a square projection 47 by means of which a handle can be attached for operating the screw in the sleeve. The bars 43 may be either permanently attached to the platform or may be removably secured thereto. In the event that they are removably secured, it is only necessary to have two sets of bars and jacks as they can be readily changed from side to side of the platform. When it is desired to move the skid, the bucket 24 is filled with material and partially raised as in Fig. 1. The boom is then swung into the position indicated by dotted lines in Fig. 2. This has a tendency to relieve the weight on the skid 7. The engine is then started and the cable 34 wound around the nigger head 29, and as the cable is pulled the skid 7 is moved, so that the front end of the skid will be under the front wheel of the platform. The boom is then swung to the opposite side, and the operation repeated on skid 6, by means of the cable 35.

In the event the load carried by the bucket is not great enough to relieve sufficient weight on the skid to allow it to be moved underneath the wheels, the jack screws are brought into use. The plates 46 rest either on the ground or if that is too soft, on timbers. The tightening of these screws will have a tendency to further lift up that side of the platform and release the weight on the skid when it can readily be moved. When it is desired to move the derrick backward on the skid, the skids having been previously moved so that the front end of the derrick is adjacent the front end of the skid, I employ a cable 48. This cable has its one end secured in the frame 49 of the snatch block 50. This block is pivotally attached to the front end of the platform 18. The cable 48 is then passed around a sheave wheel 51, then around the snatch block 50. From there it passes around a second sheave

wheel 52, then underneath the timbers 30 and around the snatch block 53. The free end 54 being adapted to be wrapped around one of the nigger heads so that by pulling thereon, the entire device will be rolled backward on the rails 16. During this operation the full weight of the machine or derrick rests directly on both skids so that the derrick will move, but its weight will hold the skids against movement on the ground.

Having fully described my invention, what I claim is:

1. The combination with a derrick provided with a platform, supporting wheels secured to said platform, a hoisting engine having nigger heads and hoisting drums, of a pair of skids provided with longitudinally extending track rails on which said derrick may be supported, a plurality of snatch blocks carried by said skids and platform, a plurality of cables mounted around said snatch blocks and having one of their ends secured to the platform and their other ends adapted to be wrapped around the nigger heads for moving the skids, means carried by the platform for relieving the weight alternately on each skid, so that they may be moved, and means for moving the platform along the skids.

2. The combination with a derrick provided with a platform having supporting wheels, a hoisting engine having hoisting drums and nigger heads, of a pair of skids provided with longitudinally extending track rails on which said derrick may be supported, a plurality of blocks carried by said skids and platform, a plurality of cables mounted around said blocks and having one of their ends secured to the platform and their other ends adapted to be wrapped around the nigger heads for moving the skids, and means for relieving the weight alternately on each skid so that they may be moved.

In testimony whereof I have signed my name to this specification.

GEORGE G. PRENDERGAST.
